UNITED STATES PATENT OFFICE.

ALEXANDER T. KASLEY, OF TINICUM TOWNSHIP, DELAWARE COUNTY, PENNSYLVANIA, ASSIGNOR TO WESTINGHOUSE ELECTRIC & MANUFACTURING COMPANY, A CORPORATION OF PENNSYLVANIA.

CONDENSING APPARATUS.

Application filed June 9, 1919. Serial No. 302,753.

To all whom it may concern:

Be it known that I, ALEXANDER T. KASLEY, a citizen of the United States, and a resident of Tinicum Township, in the county of 5 Delaware and State of Pennsylvania, have made a new and useful Invention in Condensing Apparatus, of which the following is a specification.

In my copending application, Serial No. 10 302,259, filed on the sixth day of June, 1919, and which has matured into Patent No. 1,405,848, Feb. 7, 1922, I have illustrated a locomotive equipped with auxiliary power developing apparatus which is adapted to 15 receive steam exhausted from the locomotive cylinders and to expand the steam to a pressure below atmosphere. The application discloses a low pressure turbine receiving steam exhausted from the cylinders of the 20 locomotive and a condenser into which the turbine exhausts.

My present invention relates to such auxiliary power developing apparatus and more particularly to the steam condensing 25 apparatus and has for an object to produce new and improved apparatus for cooling the water withdrawn from the condenser.

These and other objects, which will be 30 made apparent throughout the further description of my invention, are attained by means of apparatus embodying the features herein described and illustrated.

In the drawings accompanying and forming a part hereof, Fig. 1 is a transverse sectional view of a locomotive tender equipped 35 with apparatus embodying my invention.

Fig. 2 is a fragmental longitudinal view of a portion of the cooling chamber shown in Fig. 1.

Fig. 3 is a diagrammatic longitudinal section 40 of a locomotive tender and illustrates a modified form of apparatus embodying my invention.

Fig. 4 is a diagrammatic transverse sectional view of the locomotive tender shown 45 in Fig. 3.

As illustrated, the locomotive tender is divided into at least two compartments, one in which the condenser and auxiliary power 50 developing apparatus may be located, and the other in which water withdrawn from the condenser is cooled. A reference to Figs. 3 and 4 will make it apparent that the tender may be provided with other compart-

ments, namely, compartments for carrying 55 the fuel and water supply.

Referring to Fig. 1, the tender shown is provided with a bottom compartment 4 in which an auxiliary power developing mechanism including a low pressure turbine 5 and 60 an electric generator 6 are mounted. The turbine drives the generator 6 through the agency of a reduction gear 7 and, as described in said copending application, receives steam exhausted from a cylinder or 65 the cylinders of the locomotive. A condenser 8 is also located in the compartment 4 and is adapted to receive steam exhausted from the turbine 5. I have shown the condenser as of the ejector type, but it will be 70 apparent that any desired type capable of being employed in the limited space available may be used. A pump 9 communicates with the discharge port of the ejector 8 and is adapted to withdraw water therefrom and 75 deliver it in the form of spray to a cooling chamber 10, which is located in the upper portion of the tender above the compartment 4.

As illustrated, the outlet of the pump 9 80 communicates with a pipe or passage 11 and delivers water through this passage to a spray pipe or pipes 12. The pipes 12 are so arranged that they deliver the water in the form of spray to the interior of the cooling 85 chamber 10, the arrangement being such that the spray falls in a more or less uniform mass of separate drops throughout substantially the entire interior of the cooling chamber.

The water is cooled by subjecting the spray falling through the chamber to a current of air. With such an arrangement a 90 relatively large water surface is prevented to the flow of air and consequently a correspondingly large cooling effect is obtained. The air is preferably so admitted to the chamber that the air flow is substantially 95 uniform throughout all parts of the chamber and is also in a substantially counter-current direction, with relation to the travel of the spray through the chamber. As illustrated in Fig. 1, this is accomplished by providing a series of air inlet ports 13 which extends substantially across the 100 tender and from one end to the other thereof and is located intermediate the spray pipes 12 and the bottom of the chamber 10.

These ports 13 are preferably located near the bottom of the chamber so that the period during which each particle of spray is subjected to the air flow is as long as possible. 5 In Fig. 2, I have diagrammatically shown the arrangement of the air ports 13. As there illustrated, each port is in effect the open top of a trough 14 which extends transversely across the tender and communicates 10 at each end with a passage 15 formed between the chamber 10 and the adjacent outer wall of the tender. Each trough 14 is provided with inclined side walls so that a converging passage 16 is formed between 15 each pair of adjacent troughs for the delivery of water or spray to the bottom of the compartment.

The delivery of air through the ports 13 is accomplished by employing an exhauster 20 for the chamber 10. As illustrated, the chamber is provided with two exhaust ports 17 and 18. A combination fan and separator 19 is so located with relation to these ports that it withdraws air from the chamber and discharges into the atmosphere. As shown, the fan 19 is mounted on a vertical shaft 20 immediately adjacent to the port 17 so that the suction of the fan communicates with the port. A passage 21 25 communicates with the port 18 and is adapted to deliver air to the opposite side of the fan, so that the inflow of air to the fan from the port 17 is balanced by the inflow from the port 18. The fan is provided with 30 an annular discharge passage 22 which terminates in an upwardly turned discharge port 23. With this arrangement, the exhausting action of the fan induces a flow of air through each of the ports 13 and consequently creates a substantially uniform 35 flow throughout that portion of the chamber located above the air inlet ports 13. In order to prevent loss of water which may be mechanically entrained with the air passing 40 through the fan, I have provided the annular discharge passage 22 and also an annular screen 25 which is located within the passage adjacent the port 23 and, in effect, forms the outer periphery of the passage 45 22. This screen is located in the direct line of travel of air discharged from the fan 19, and while it, to some extent, acts as a baffle in turning the flow of air upwardly through the port 23, it also acts as a trap in collecting 50 particles of water thrown off by the fan or entrained with the air passing over the screen. As shown, I have provided means for draining the water so collected back into the chamber 10. The means illustrated 55 is a series of ports 26 formed in the bottom of the passage 22 and located between the end wall of the passage and the screen 25.

The shaft 20 on which the fan is mounted 60 extends downwardly through a cylindrical

tube 27 which, as shown, is secured to the bottom of the chamber 10 and forms a water tight seal around the shaft 20. The shaft is, of course, provided with a suitable step bearing and, as shown, is driven by a turbine 28 through the agency of a reduction gearing 29. The gearing 29 may also drive the pump 9, under which conditions the pump 9 would preferably be located below the shaft 20. 75

In order to prevent objectionable swishing of the water collected in the bottom of the chamber 10, I have provided a series of baffles 31 which, as illustrated, extend longitudinally of the tender and consequently 80 at right angles to the troughs 14. As illustrated in Fig. 2, the upper portion of each baffle 31 is cut out to receive the troughs 14. These baffles may extend to the tops of the troughs and they may extend below the bottoms of the troughs. With the construction illustrated, it will be apparent that the troughs themselves check the tendency of the water to swish and also to splash as a result of quick stops and starts of the 85 tender, whereas the baffles 31 will tend to prevent swishing due to the rolling motion of the tender. The chamber 10 is shown provided with a water delivery port 32, which communicates with the intake of the 90 condenser 8 through a pipe 33. 95

In operation the fan creates a current of air through the interior of the chamber 10. The vacuum within the condenser occasions a flow of water at a relatively high velocity 100 through the pipe 33 and into the condenser 8. This water is withdrawn from the condenser by means of the pump 9 which, with the type of condenser illustrated, also withdraws the air or non-condensable fluids from the condenser and discharges them with the water into the chamber 10. The water entering the chamber 10 is broken into a mass of separate drops or spray and falls through the chamber, where it is subjected 105 to the air flow induced by the fan 19. The arrangement of the ports 13 in conjunction with the flow of air issuing from these ports is such as to deflect the separate particles of water tending to enter the air ports and 110 to cause all of the water to pass through the converging passage 16 into the bottom of the chamber 10. 115

In Figs. 3 and 4, I have shown a modified arrangement of the apparatus embodying 120 my invention. As illustrated, the tender is divided into a fuel carrying compartment 35, two water compartments 36, a cooling chamber 37 and a compartment 38 in which an auxiliary power developing mechanism 130 including a turbine 39, a gearing 40, and an electric generator 41 are mounted. The turbine 39 receives low pressure steam through a conduit or passage 42, and the steam exhausted from the turbine is delivered to a 130.

condenser 43, which is also located in the compartment 38.

As shown, the cooling chamber 37 is of triangular section longitudinally of the tender. The circulating pump 44 withdraws water from the condenser and delivers it through a pipe or passage 45 to a spray pipe or pipes 46. These pipes 46 are shown located across a portion of the top of the chamber 37 and are so arranged that substantially the entire chamber is filled with the water spray delivered by them. The chamber is illustrated as provided with air discharge ports 47 arranged to occasion a more or less uniform flow of air throughout the entire chamber. A fan 48 is arranged with relation to these ports in a manner described in connection with Fig. 1, and is adapted to perform the double function of withdrawing air from the chamber and also separating the entrained water from the air so withdrawn. As shown, air inlet ports 50 are provided in the rear wall of the chamber and are so arranged as to produce a substantially uniform flow of air throughout the entire chamber. This flow is also in substantially the direction of a countercurrent with relation to the travel of spray through the chamber, since its general direction of flow is upward toward the ports 47, whereas the general direction of flow of the spray is downward. It will, of course, be apparent that the inrushing air deflects the flow of water so that the spray will flow at an angle to the vertical in passing through the chamber. As illustrated, baffles 51 are provided along the inclined wall of the chamber for preventing undue swishing of the water and also for preventing the water entering the fan 48, in case of an emergency or other quick stop. The water collects in the bottom of the chamber and is delivered by a passage 52 to the condenser 43. It will, of course, be apparent that a surface or jet condenser may be employed and that the necessary auxiliary apparatus may be driven by the turbine 53 through the agency of gears or other connections. As shown, a turbine 53 drives both the circulating pump 44 and the fan 48.

While I have illustrated two embodiments of my invention, it will be apparent that various changes, modifications, additions and omissions may be made in the apparatus illustrated without departing from the spirit and scope of the invention as set forth by the appended claims.

What I claim is:

1. In combination with the tender of a locomotive, a condenser located in said tender, a cooling chamber located in the tender, a pump for withdrawing water from the condenser and delivering it in the form of a spray to said chamber, air delivery ports

located near the bottom of said chamber and so distributed as to create a substantially uniform flow of air throughout substantially all portions of said cooling chamber and in a substantially countercurrent flow relatively to the direction of travel of the spray through said chamber, and a fan for withdrawing air from said chamber and thereby inducing a flow through said air delivery ports.

2. In combination with the tender of a locomotive, an auxiliary power developing mechanism for the locomotive mounted on the tender, a condenser mounted on the tender and receiving exhaust steam from said auxiliary mechanism, a cooling chamber located in the tender, means for withdrawing water from said condenser and delivering it in the form of spray to said cooling chamber, a series of air delivery ports distributed throughout said chamber for delivering a flow of air through said chamber in substantially a countercurrent flow with relation to the travel of the spray through the chamber, and means for withdrawing air from the chamber and thereby inducing air flow through said ports.

3. In combination with the tender of a locomotive, an auxiliary power developing mechanism for the locomotive mounted on the tender, a condenser mounted on the tender and receiving exhaust steam from said mechanism, a cooling chamber formed within the tender, means for withdrawing water from the condenser and delivering it in the form of spray to said cooling chamber, air delivery ports for delivering air to said chamber and so disposed that the interior of the chamber is subjected to a substantially uniform flow of air in a substantially countercurrent direction with relation to the travel of spray through the chamber, and means for occasioning a flow of air through said ports.

4. In combination with the tender of a locomotive, a condenser mounted on the tender, a cooling chamber formed within the tender and provided with a series of air admission ports, means mounted on the tender for withdrawing water from said condenser and for delivering it in the form of spray to said chamber, and a combination fan and water separator for withdrawing air from said chamber and for mechanically separating the water entrained with said air.

5. In combination with the tender of a locomotive, a cooling chamber formed in said tender, and provided with air delivery ports, a condenser, means for withdrawing water from the condenser and delivering it to said chamber in the form of spray and a combination fan and water separator for inducing a flow of air through said chamber.

- ber, and for thereby withdrawing air therefrom, and for mechanically separating the water entrained with said air.
6. In combination with a condenser, a cooling chamber provided with air inlet ports, means for delivering water withdrawn from the condenser to the cooling chamber in the form of spray, and a combination fan and separator for withdrawing air from the chamber and for separating the water entrained with the air.
7. In combination with the tender of a locomotive, a cooling chamber, means for delivering water in the form of spray to said chamber, air inlet ports located intermediate the top and bottom of said chamber for delivering a substantially uniform flow of air through the entire upper portion of the chamber, and means communicating with a port formed in the bottom of said chamber for delivering water from the chamber.
8. In combination with the tender of a locomotive, a cooling chamber, means located near the top of the chamber for delivering water in the form of spray to said chamber, means located intermediate said spray delivery means and the bottom of the chamber for delivering a substantially uniform flow of air to the chamber, and baffles formed in said chamber for preventing swishing of the water in the bottom of the chamber.
9. In combination with the tender of a locomotive, a cooling chamber, means located near the top of the chamber for delivering water in the form of spray to said chamber, a series of spaced troughs located between said means and the bottom of the chamber and forming alternately arranged air delivery passages and passages through which water spray passes to the bottom of the chamber, and means for withdrawing air from said chamber and thereby occasioning a flow of air through said ports.
10. In combination with a locomotive tender, a geared turbo generator set mounted on said tender, a condenser receiving steam exhausted from the turbine forming a part of said set, a cooling chamber formed within the tender, a pump for withdrawing water from the condenser and for delivering it to said cooling chamber, a fan for withdrawing air from said cooling chamber, a turbine for driving said fan and said pump, and a reduction gearing between said turbine and the pump and the fan.
11. In combination with a low pressure turbine forming a part of an auxiliary power developing apparatus for a locomotive engine, a condenser receiving steam exhausted from said turbine, a cooling chamber, means for withdrawing water from the condenser to the cooling chamber in the form of spray, and means for maintaining a flow of air through the cooling chamber in substantially a countercurrent direction with relation to the travel of spray through the chamber.
12. In combination with a locomotive tender, a compartment in which a low pressure turbine and a condenser serving said turbine are located, a cooling chamber located in said tender, means for withdrawing water from said condenser and delivering it to said cooling chamber in the form of spray, air delivery ports located in one wall of said chamber, means for withdrawing air from said chamber and thereby inducing a flow of air through said ports, means for separating water from the air withdrawn from the chamber, and a port formed in said chamber for delivering cooled water to said condenser.

In testimony whereof, I have hereunto subscribed my name this 5th day of June, 1919.

ALEXANDER T. KASLEY.

Witness:

JAMES GOSO.
